UNITED STATES PATENT OFFICE

JAMES OSWALD OLIVER, OF NEW YORK, N. Y.

PLASTERING SUPPORT

Application filed July 30, 1929, Serial No. 382,188. Renewed August 19, 1932.

This invention relates to plastering supports.

It is among the objects of the present invention to provide a novel and improved device designed to aid in the support of plastering and plastering lath.

It is a further object of the present invention to provide a preformed, readily applied supporting element to which plastering material is adapted to adhere, whereby the same will assist in supporting the plaster and will act to retain the lath in proper position.

A further object of the present invention is to provide a preformed cementitious supporting element which may be associated with a lath support and with a lath, and to which plastering material will adhere, thus holding the plaster and assisting in supporting the same.

Other objects of the present invention include the provision of a novel, simple structure which may be readily applied and which is readily adapted to the demands of economic manufacture.

Other objects and features of the present invention will be apparent from a consideration of the following specification taken in conjunction with the accompanying drawing, in which

Figure 1 is a plan view partly broken away showing one form of the present invention;

Fig. 2 is a sectional view taken on lines 2-2 of Fig. 1.

Referring more particularly to the drawing, a wall structure is disclosed including parallel vertical metallic lath-supporting elements 10, to which, as in conventional practice, the metallic lathing material, as indicated at 12, is secured.

In connection with the present invention it will be understood that the same may be applied to many varieties of the structure herein shown, and that the invention is not confined to its combination with the specific type of wall structure illustrated. As, for instance, the invention is applicable to all types of metallic lath, and is not dependent upon any specific type of standards. The invention is thus seen to be adapted for use in connection

with all forms of plastering supports for both wall and ceiling construction.

The plastering support of the present invention includes a preformed block 14, which is illustrated as preferably elongated, and includes sloping sides which provide a maximum lath-engaging surface 15. The block 14 is reinforced by a cast-in, angularly-bent, reinforcing element 16, the ends 17 of which extend from the ends of the block to be bent to engage the members 10, or their equivalents, the arrangement being such that the block may be easily connected with the members 10, whereby its surface 15 abuts the lath 12.

The block 14 may be formed of any suitable material to which the plaster, indicated by the numeral 18, may adhere, such as metal or cementitious material as here disclosed, and is preferably formed of cementitious material. The reinforcing element 16 is preferably formed of strong steel wire and is preferably cast with the block 14.

It will be understood that the invention is not confined to the specific materials herein desired, nor is the invention specially confined to the type of reinforcing element herein shown. The invention primarily resides in the provision of a reinforcing block to which plastic material may adhere, and which includes means for securing the block in abutting relation to lathing material.

As shown in Fig. 1, the block 14 may be arranged in any desired manner, preferably in break-joint position, thus providing the maximum support for the plaster and for the lathing with which it is associated.

From the foregoing it will be readily seen that when plaster is applied to the lathing material it will pass therethrough for adherence with the block 14, thus rigidly securing in proper relation the plaster 18, the lathing 12 and the block 14.

In connection with the present invention it will be further understood that in many instances the securing of the lath is unsuitable and that after the duration of time the lathing with its plaster 18 will fall from its support. The present invention provides an additional reinforcing and supporting means,

the securing elements 17 of the block being of materially stronger material than is possible to use in conjunction with the securing of the lath 12 to the members 10.

5 The invention thus provides a novel and improved structure and supporting element for plastering material. It will be understood that numerous changes and modifications of the present invention may be resorted 10 to without departing from the spirit or scope of the present invention as outlined in the appended claims.

I claim:

15 1. The combination with a lath-supporting structure, of a plaster-supporting element supported thereby in abutment with the lath supported by said structure, said element including a plaster-engaging surface to which the plaster may adhere, and reinforcing means extending through said element.

20 2. The combination with a lath-supporting structure, of a plaster-supporting element supported thereby in abutment with the lath supported by said structure, said element including a plaster-engaging surface to which the plaster may adhere, and reinforcing means extending through said element and extending therefrom to secure said element with said lath-supporting structure.

25 30 3. A plastering support, including a block and means for retaining said block adjacent to lathing material, said means including a reinforcing member extending through said block and protruding therefrom to engage a lath-supporting structure.

35 4. A plaster support, including a pre-formed plastic body and means extending therefrom for engaging said body with a lath-supporting structure, said means extending through said body to reinforce the same and being angularly disposed within said body to extend transversely thereof.

JAMES OSWALD OLIVER.
